UNITED STATES PATENT OFFICE.

JOSEPH LE ROY BANKS, OF BALTIMORE, MARYLAND.

MUSICAL INSTRUMENT.

Application filed July 19, 1922. Serial No. 576,145.

REISSUED

To all whom it may concern:

Be it known that I, JOSEPH LE ROY BANKS, a citizen of the United States, residing at 308 North Carey Street, in Baltimore city, in the State of Maryland, have invented a new and useful Improvement in Musical Instruments, of which the following is a specification.

My invention relates to improvements in musical instruments the objects of which are to provide—a new article of manufacture, 2nd, to provide a musical instrument with a means for controlling the tones; 3rd, to provide musical instruments with a note control playing attachment; 4th, to provide mouth blown musical instruments with automatically playing attachments; 5th, to provide a player instrument with a detachable musical instrument; 6th, to provide a means for packing the musical instrument to a tracker-bar; 7th, to provide a tracker-bar whereby the playing attachment is secured to the musical instrument; to provide a tracker-bar whereby the playing attachment is detachably secured to the musical instrument; 8th, to provide a tracker-bar whereby the musical instrument is detachably secured to the note controlling means; 9th, to provide a player instrument with a detachable note controlling means; 10th, to provide a tracker-bar with brackets for supporting a notes controlling means; 11th, to provide a tracker-bar with means for frictionally securing a musical instrument to a notes controlling means; 12th, to provide a tracker-bar secured to a mouth-piece jointly detachable from a musical instrument; 13th, to provide means for registering the musical instrument in the tracker-bar.

Referring to the drawings,—

Fig. 1 is my player instrument in perspective.

Fig. 2 is a perspective view of an harmonica or mouth-organ.

Fig. 3 is a cross section of my player instrument.

Fig. 4 is an elevation of the shield, tracker-bar, and packing.

Fig. 5 is a side elevation of the mouth piece, showing the brackets whereby the notes controlling means are held.

Fig. 6 is a cross section of the tracker-bar in modified form, illustrating how the musical instrument is inserted.

Fig. 7 is the rear end view of the tracker-bar and supporting brackets.

Fig. 8 is a side view of a modified form of the tracker-bar and supporting brackets for the notes controlling means.

Fig. 9 is a sectional view of an harmonica musical instrument.

Fig. 10 is a plan view of a spool commonly used to wind up note controlling sheets or other rolled sheets.

Referring to the drawings,—

The numeral 1 is the orifice in the mouth-piece 2, and 3 is the flared edge of the aperture, 4 between the mouth-piece 2 and the tracker-bar 4', through which the note controlling means 7 wound upon the axle 6 and secured by the clip 22 to the spool 5 and supported on the upper side of the mouth piece 2 by the brackets 12, passes to allow the flow of air to the openings 7' in the notes controlling means 7, thence through the openings 21' in the tracker-bar 4' over which the note controlling means 7 passes, and thence through the openings 21' in the packing 21, and through the air passages 14' to the reeds 14'' on the reeds plates 14'' of a musical instrument.

The notes controlling means 7 then passes between the shield 3' and the tracker-bar 4' and out of the flared edge 25 of the orifice 26 between the mouth-piece 2 and the tracker-bar 4' and onto the axle 17 of the spool 16 and secured to it by the clip 23. 25' and 9 are lugs to retain the musical instrument 13 in place after inserting it; and the clamping screws 24 in the lugs 9 serve to press the musical instrument 13 against the packing 21 to prevent the air from escaping when the player instrument is being operated. 8 is the other end of the spool 5, and 10 is the bearing in the bracket 12 in which the axle 6 revolves.

The slot 11 in the bracket 12 permits the quick removal or insertion of the notes controlling means 7. Likewise 15 is a bracket on the lower side of the mouth piece 2 and is also provided with a quick releasing slot 17'' in which the axle 17 is inserted to revolve in the bearings 17' by the crank 18 being turned by its handle 19.

20 is the cover over the reeds plates 14'' forming the sound chamber and mouth piece of the musical instrument 13 when used independently of my player instrument.

I may use glue or lacquer or any other material for the packing between the musical instrument and the tracker-bar.

It will be seen that the brackets support

ing the note controlling means are secured to the tracker-bar as well as the mouth-piece.

I do not care to limit myself to any particular construction of my player instrument coming within the scope of the claims; nor to any particular type of musical instrument to be used in my player instrument.

Instead of the normal way of supplying the air by the mouth, I may use some other means, such as compressed air, or the exhaust from an engine, or I may use a blower driven by some power such as an electric or other motive power; and instead of turning the notes controlling means by hand, I may use some other power.

It will be seen that the musical instrument is adjustably as well as detachably mounted in my player instrument, but I may permanently secure the musical instrument in my player instrument.

I claim:

1. In a player instrument, means provided with a plurality of sides for carrying and supporting a musical instrument upon one side of said means, and means for carrying and supporting a perforated-notes music sheet carrying roller upon the opposite side of said first named means, and means in said first named means communicating said musical instrument with said perforated-notes music-sheet carrying roller.

2. In a player instrument, means provided with a plurality of sides for carrying and detachably supporting a musical instrument upon one side of said means, and means for carrying and supporting a perforated-notes inmusic-sheet carrying roller upon the opposite side of said first named means, and means in the said first named means communicating said musical instrument with said perforated-notes music-sheet carrying roller.

3. In a player instrument, means provided with a plurality of sides for carrying and supporting a musical instrument upon one side of said means, said means being open at one end for inserting, positioning and holding said musical instrument; and means provided for carrying and supporting a perforated-notes music-sheet carrying roller upon the opposite side of the said first named means, and means in said first named means communicating said musical instrument with said perforated-notes music-sheet carrying roller.

4. In a player instrument, means provided with a plurality of sides for carrying and supporting a musical instrument upon one side of said means, said means being open at opposite ends for inserting, positioning and holding said musical instrument, and means provided for carrying and supporting a perforated-notes music-sheet carrying roller provided with means for engaging a

perforated-notes music-sheet upon the opposite side of said first named means, and means communicating the first named side with the second named side.

5. In a player instrument, means provided with a plurality of sides for carrying and supporting a musical instrument upon one side of said means, and means provided for carrying and supporting a perforated-notes music-sheet carrying roller upon the opposite side of said first named means and comprising a tracker-bar for communicating the first named side with said opposite side.

6. In a player instrument, means for supporting a perforated-notes music sheet carrying roller in operative relation to a musical instrument, and means open at its end for inserting, positioning and holding the musical instrument.

7. In a player instrument, a tracker-bar provided with means open at its end for inserting, positioning and holding a musical instrument.

8. In a player instrument, a tracker-bar provided with means open at opposite ends for inserting, positioning and holding a musical instrument.

9. In a player instrument, a tracker-bar provided with means open at its end for inserting, positioning and holding a musical instrument, and also provided with means for supporting a perforated-notes music-sheet carrying roller in operative relation to said musical instrument.

10. In a player instrument, means for supporting a harmonica, said means being open at each end for the insertion of the harmonica, and comprising a tracker-bar integral with said means.

11. In a structure set forth in claim 10 with packing between the tracker-bar and the harmenica.

12. In a player instrument, a support for a mouth blown musical instrument struck from sheet material and provided with cut out portions forming a tracker-bar, and integral parts of said material formed to provide supports adjacent said tracker-bar for supporting a perforated-notes music-sheet carrying roller in operative relation to said tracker-bar and also provided with integral parts of said material formed to provide supports extending in an opposite direction to the former named integral parts, for supporting a roller and means for operating it.

13. In a player instrument, a support for a musical instrument provided with a plurality of air passageways and provided with means for producing each note independently of the others; supports secured integrally to the first named support, for supporting a perforated-notes music-sheet carrying roller in operative relation to said note producing means; and supports integrally se-

cured to the first named support for spacing and supporting a second roller spaced at an operative distance from the former named roller supports, and a mouth piece for operating said musical instrument.

14. A player instrument comprising a musical instrument provided with a plurality of note producing means, a support therefor provided with a plurality of sides, means 10 for securing said musical instrument to one of said sides, means communicating said musical instrument with the opposite side of said supporting means, said opposite side provided with means for supporting a music-sheet carrying roller in operative relation to said musical instrument and said communicating means, means secured to said roller for engaging a music sheet, means secured to the said opposite side for supporting a second roller also provided with means for engaging said music-sheet, means for operating said rollers, and means for operating said musical instrument.

15. A player instrument comprising a musical instrument provided with plurality of note producing means and a plurality of air passageways, a support therefor provided with a plurality of sides, means for securing

said musical instrument to one of said sides, means communicating said musical instrument and said air passageways with the opposite side of said supporting means; means for supporting a perforated-notes music-sheet against said communicating means and means for engaging the end of said perforated-notes music-sheet and rolling it upon a music sheet carrying roller, means for supporting said music-sheet carrying roller and for detachably securing said roller to the first named support, means for operating 40 the said roller, means for lengthwise supporting a second roller in alignment with the first named roller, and means provided on the second roller for engaging and rolling up said music sheet, means for operating 45 the said second roller, and means for supporting a mouth-piece to the first named support.

16. A device for playing a harmonica comprising a tracker-bar, means for supporting a music-note sheet for movement across said tracker-bar, and means for supporting a harmonica for adjustment lengthwise of said tracker-bar.

JOSEPH LE ROY BANKS.
